Primary Examiner — Susan Moon Lee*(74) Attorney, Agent, or Firm* — Brinks Gilson & Lione(57) **CLAIM**

I claim the ornamental design for an optical scanner, as shown and described.

DESCRIPTION

FIG. 1 is a front perspective view of an optical scanner of the present invention;

FIG. 2 is a rear perspective view thereof;

FIG. 3 is a front view thereof;

FIG. 4 is a rear view thereof;

FIG. 5 is a top view thereof;

FIG. 6 is a bottom view thereof, wherein the circular areas located in the lower corners encompass a cylindrical voided space as seen in FIG. 9;

FIG. 7 is a first side view thereof;

FIG. 8 is a second side view thereof; and,

FIG. 9 is a cross-section view taken along the line 9-9 of FIG. 5.

1 Claim, 5 Drawing Sheets(56)
